J. S. ARMOUR

OIL STRAINER

Filed Sept. 26, 1925

INVENTOR.

John S. Armour,
by R. K. Kellogg
his attorney.

UNITED STATES PATENT OFFICE.

JOHN S. ARMOUR, OF HARRISON, OHIO, ASSIGNOR TO THE CAMPBELL HAUSFELD COMPANY, OF HARRISON, OHIO, A CORPORATION OF OHIO.

OIL STRAINER.

Application filed September 26, 1925. Serial No. 58,941.

Oil used for fuel purposes, such as crude oil, fuel oil and the like, contains sediment, foreign substances and viscous ingredients, which, if allowed to reach the burners, render the flames and heat irregular, and clog the burners, which is especially harmful in melting furnaces and other heat treating furnaces, in which it is desirable to maintain a steady heat.

10 I have therefore provided an improved strainer which arrests the passage of such sediment, viscous ingredients and foreign substances, and have provided means whereby the strainer may be freed from such arrested sediment, ingredients and substances, and have further provided means whereby such arrested materials may be trapped and readily removed.

20 The invention will be further readily understood from the following description and claim, and from the drawing, in which latter:

Fig. 1 is a plan view of my improved device.

25 Fig. 2 is a side elevation of the same, partly broken away.

Fig. 3 is a horizontal section of the same, taken in the plane of the irregular line 3—3 of Fig. 4.

30 Fig. 4 is an axial section of the same, taken on the line 4—4 of Fig. 1; and,

Fig. 5 is an enlarged detail on the last-named section line.

35 My improved device may be placed at any desirable point in the oil feeding line, and the propulsion of oil may be obtained by gravity, pressure or suction, the flow of the oil being in the direction of the arrows shown in Fig. 4. While I have instanced oil as the liquid being strained, it is obvious that other liquids may be strained by my improved device.

40 A casing 11 is provided, which has a cavity 12, formed by the wall of the casing and a baffle wall 13, which latter separates said cavity from an inlet passage 14, communicating with the cavity by an opening 15 at its lower end, to direct the inflow of oil toward the lower end of the cavity. An inlet opening 16 has an inlet-pipe 17 connected therewith.

45 An outlet opening 21 has an outlet-pipe 22 connected therewith. This outlet opening may be in a plug 23 threaded in a 50 threaded socket 24 in the casing.

A tube 25 is shown cylindrical, but may be of other cross-sectional form. Its lateral walls are perforated, as shown by the holes 26. Its end 27 in the cavity 12 is preferably imperforate. It is located in an opening 28 60 in the casing, and is provided with an annular flange 29 which rests on a shoulder 30 surrounding said opening 28. The flange may be on a collar 31 to which the tube is 65 fixed.

The plug 23 preferably has a socket 36, the lateral annular wall 37 of which is arranged to clamp the flange 29 upon the shoulder 30 for providing an oil-tight joint. The interior of the tube 25 communicates 70 freely with the socket 36 through the collar 31.

A wiping strip 41 is received about said tube. It is shown in the form of a ring which surrounds said tube, preferably in 75 close proximity to the outer periphery of the tube. Its cross-sectional form corresponds with the cross-sectional form of the tube, instanced as annular. The ring has inner scraping edges 42, 43, and is arranged 80 to scrape the outer periphery of the tube and free the same from sediment, ingredients and substances, which may have lodged against the outer periphery of the tube, and to free the perforations from such obstructions. 85

The ring is shown provided with trunnions 45 received in slots 46 of a fork 47, fixed to a rod 48, as by having the threaded end of said rod pass through a hole 49 in said fork, nuts 50, 51, at the respective ends 90 of said hole clamping the fork to said rod. The rod extends to a point outside the casing, where it is provided with a handle 53, by means of which it may be manipulated. An oil-tight packing is provided about the 95 rod, shown as a compressible packing 54, in a socket 55 between a shoulder 56 surrounding the hole through which said rod extends and a gland 57 about said rod in said socket, a cap 58 threaded to the wall of said socket 100 compressing said packing.

The end of the cavity 12 is provided with an opening 61, closed by a plug 62, threaded to the wall of said opening, and provided with a socket 63, which forms a trap. 105

In assembling the parts, the tube 25 is inserted in the opening, and the ring 41, the fork 47, and the nuts 50, 51, passed through the opening 61, the ring being placed about the tube in the cavity and the trunnions of 110

the ring being placed in the fork, and the fork clamped between the nuts 50, 51, about the rod, which latter has been inserted through the hole in the shoulder 56.

- 5 The parts are of simple construction and are readily assembled.

During the passage of the oil in the direction of the arrows shown in Fig. 4, the undesirable sediment, ingredients and substances are arrested by the strainer, lodging on the outer periphery of the strainer. The strainer is readily freed from such undesirable materials by the operation of the cleaning ring 41, which is caused to slide lengthwise of the tube in both directions, the scraping edges of the ring scraping such undesirable materials from the tube. These undesirable materials descend into the socket 63 in the closing plug 62, below the flow of the oil passing through the perforations in the tube, and may be readily removed by removal of the plug.

The scraping ring may be operated at stated intervals, according to the character of oil being used, or as the result of observation of the flame or heat, and the plug 62 may be removed and replaced at longer intervals.

A constant free flow of oil may be ob-

tained by my improved device, resulting in 30 constant flames and heat.

Having thus fully described my invention, what I claim as new, and desire to secure by Letters Patent, is:

A strainer comprising a casing having an 35 inlet opening at its lower portion, an outlet opening at its upper portion, a removable plug in the latter, a perforated tube received in said casing through said outlet opening and extending in said cavity above 40 said inlet opening, a wiping ring received about said tube and the perforations in said tube, a fork with which said ring has pivotal connections at opposite sides of said tube, a rod connecting with said fork and 45 extending outside said casing, a packing between said casing and said rod in which said rod has axial movement for moving said wiping ring lengthwise of said tube across said perforations, said casing provided with an opening below said tube and ring, and a removable plug to close said opening and form a trap in said casing below 50 said inlet opening.

In testimony whereof I have hereunto signed my name.

JOHN S. ARMOUR.
